UNITED STATES PATENT OFFICE.

FRANK KNAPP AND GEORGE B. KNAPP, OF KANSAS CITY, MISSOURI.

NAIL LEATHER-HEADING MACHINE.

994,008.

Specification of Letters Patent. Patented May 30, 1911.

Application filed September 13, 1909. Serial No. 517,446.

To all whom it may concern:

Be it known that we, FRANK KNAPP and GEORGE B. KNAPP, citizens of the United States, residing at Kansas City, in the county of Jackson and State of Missouri, have invented certain new and useful Improvements in Nail Leather-Heading Machines, of which the following is a specification.

10 This invention relates to nail leather-heading machines, and has for its object to produce a machine of this character which performs its function efficiently, reliably and expeditiously.

15 With this general object in view and others as hereinafter appear, the invention consists in certain novel and peculiar features of construction and organization as hereinafter described and claimed; and in 20 order that it may be fully understood reference is to be had to the accompanying drawings, in which—

Figure 1, is a front view of a nail leather-heading machine embodying our invention. 25 Fig. 2, is a top plan view of the same. Fig. 3, is a right-hand side view of the machine. Fig. 4, is an enlarged section taken on the line IV—IV of Fig. 3. Fig. 5, is a vertical section on the line V—V of Fig. 2. 30 Fig. 6, is a section on the line VI—VI of Fig. 3. Fig. 7, is a section on the line VII—VII of Fig. 4 with the feed wheel omitted. Fig. 8, is a diagrammatic view showing the electrical connections between 35 the make-and-break device and the electromagnet, forming parts of the machine.

Before proceeding with the detailed description of the machine, it is desirable to state that nails equipped with leather or 40 equivalent heads or washers are used in electrical work and that heretofore it has been customary for the workmen engaged in stringing electric wires in buildings to slip perforated leather disks upon the nails by 45 hand, a rather slow and tedious operation.

Referring now to the detail construction, 1 indicates a pedestal having a top 2 provided with an extension 3 projecting to the right and an extension 4 projecting and 5 sloping upward to the left, a nail-receptacle 5 being preferably supported upon extension 3, and a leather head receptacle 6 upon extension 4, and having the discharge end 10 of its bottom of concave arcuate form. The 55 top is provided with an arcuate slot 6^a struck from the same center by preference as the

concave edge of receptacle 6 and said slot rearward of such center terminates in a contracted or narrow portion 6^b of slightly larger width, by preference, than the diameter of a ten-penny nail. At its rear edge the top is provided with an upwardly projecting standard 7 as a support for mechanism hereinafter described.

8 is a stud bolt secured in and projecting upward from top 2 axially of the concave edge of the bottom of receptacle 6 and the slot 6^a, and resting flatly upon the top 2 is a feed wheel 9 in the form of a ratchet wheel, of the same thickness by preference, as the bottom of receptacle 6 and of such size that its teeth almost scrape the concave edge of the bottom of said receptacle in their rotative movement.

The ratchet wheel as shown is equipped with eighteen teeth and near its periphery with a corresponding number of holes 10, of size to receive the leather heads hereinafter identified and of slightly smaller diameter than slot 6^a over which they successively pass 80 in the rotation of the wheel, and to impart rotative step by step movement to said feed wheel, the following mechanism is provided:

11 is a rock lever pivoted on stud bolt 8 and consisting of a rearwardly projecting 85 arm 12 and a forwardly projecting arm 13, the latter pivotally carrying a pawl 14 and a spring 15 to hold the pawl pressed yielding against the ratchet-toothed edge of the feed wheel.

16 is a bracket swiveled to the rear end of arm 12, and pivotally connected by a link 17 to a rock-bar 18 pivoted on bolt 19 carried by standard 7, the upper end of said rock bar 18 carrying a pin 20 engaging the slot of a vertically reciprocating bar 21, said slot consisting of a pair of vertical end portions 22 and 23 out of alinement with each other and connected together by a compound curved or cam portion 24. The reciprocating bar 21 is provided with a longitudinal slot 25 slidably mounted on and guided by pivot 19 and is also provided with an arm 26 pivotally connected to a bolt 27 which is in turn pivoted by a link 28 to the free end of the crank arm 29 of a shaft 30, journaled in the upper end of standard 7, motion being imparted continuously in one direction to said shaft by a driven wheel 31 mounted thereon, said wheel being of any suitable or preferred type, but shown as a sprocket wheel. The shaft is also provided

with the rotary member of a circuit making-and-breaking device, said member consisting of a shaft having a periphery consisting of insulating material 32 and conducting material 33. The companion member of the circuit making-and-breaking device consists of a contact pin 34 fitting in the socketed bracket 35 secured to standard 7 by preference, and insulated from the same at 36, or 10 otherwise, a spring 37 fitting in the socket of said bracket and holding the contact pin pressed yieldingly against the periphery of the rotary member, so that the circuit shall be made and broken once in each revolution 15 of the same.

38 is a vertical reciprocating driver or plunger mounted slidably in the keeper or guide 39 secured to standard 7 said plunger being vertically alined with each hole 10 of the feed wheel, as such holes successively assume positions directly rearward of the axis of the wheel as hereinafter explained. The upper end of the driver or plunger is pivoted to bolt 27, so that once in each revolution 25 of the shaft 30, the driver or plunger and bar 21 shall move downward and upward.

40 is a link pivotally connected at its lower end to bolt 27 and provided at its 30 upper end with a bolt 41 engaging the longitudinal slot 42 in the head of a T-shaped lever 43, pivoted as at 44 to standard 7 and pivotally connected at the outer end of its stem by a link 45 to a rock arm 46, pivoted 35 at 47 to standard 7. The free end of the rock arm 46 is pivotally connected by a link 48 to the upper end of a vertical slide bar 49 provided with a longitudinal slot 50 guided upon bolts 51 secured to a vertical 40 rib 52 projecting forward from said standard. Projecting forward from the lower end and side margins of slide bar 49 is a pair of vertical arms 53 provided with obtuse-angle-shaped slots 54 and 55 inverted 45 with respect to each other and so disposed that one of the arms of slot 54 extends vertically and the other downwardly and rearwardly, and one of the arms of slot 55 extends vertically and the other upwardly and 50 rearwardly, the angles of the slots being transversely alined as will be apparent by reference to Fig. 3.

56 and 57 are vertical rock-bars pivoted 55 to arms 57^a of a keeper hereinafter described and rock bar 56 has a pin 58 slidably engaging slot 54 and rock bar 57 a pin 59 slidably engaging slot 55.

60 and 61 are slide bolts pivoted at their outer ends to rock bars 56 and 57 respectively and mounted slidably in the keeper 62 projecting forward from a U-shaped chute 63 suitably supported by the standard or otherwise, the front wall of the chute having openings 64 and 65 through which said bolts 60 and 61 may be projected to form tem-

porary partitions for the chute. The chute is of sufficient depth to accommodate the nails employed, ten-penny nails being the size ordinarily used and sufficiently narrow to permit the heads of the nails numbered 66 to rest upon the upper edges of the walls of the chute. The chute is inclined downward and to the left at the proper angle to permit the nails to gravitate downward until the foremost one is arrested by bolt 70 60 or 61 as the case may be, as hereinafter explained, and the outer end or mouth of the chute is preferably flared as at 67 to facilitate the insertion of the nails in the chute. 75

Pivoted to pin 68 projecting forward from standard 7 is a nail supporter 69 having one end projecting under the driver or plunger when elevated and at such end disposed adjacent to the discharge end of the chute 63, said end of the nail supporter having a bifurcation 70 just wide enough to easily receive the shanks of the nails but not the heads so that said nails shall successively hang by their heads upon said supporter vertically below the driver or plunger. The opposite end of the nail supporter is of sufficient weight to yieldingly hold the supporter in the position described, a stop pin 71 projecting from the standard 90 7 for the purpose of preventing the end of the supporter from attaining an inoperative position, that is attaining a position higher than the discharge end of the chute. 95

72 is a stop secured to the top 2 or at any other suitable point and adapted to prevent the point of the nail from being drawn out of alinement with the driver or plunger and the center of the underlying hole 10 of the feed wheel, by means of the core 74 of the electromagnet 73, said core in the preferred construction fitting slidingly within the coil or magnet and adapted to be magnetized periodically as hereinafter explained. 100

75 is a pivot connecting the said core to the lower end of rock bar 18 so that the rocking movement of said rock bar shall impart longitudinal movement in one direction or the other to the core, and secured to the opposite sides of the core and projecting beyond the adjacent end of the same are non-magnetic plates 76 to guard against back and forth swinging movement of the nails as they are successively caught by the supporter. 105

77 is a wire electrically connected at its opposite ends to the coil or magnet 73, and the contact pin 34. 78 is a wire connecting the opposite end of said coil with battery 79 or an equivalent source of electric-current supply, the opposite pole of said battery being connected by a wire 80 to the rotary member of the make-and-break device. 115

The receptacle 5 is adapted to be charged with nails—none being shown in the box, 120 130

or the nails may be transferred from the usual receptacle or keg to the chute. The perforated disks 81 are adapted to be stored in receptacle 6 and deposited by hand or 5 otherwise in the holes 10 of the feed wheel, or any suitable means not shown, may be employed for automatically disposing the nails in the chute, and the perforated disks in the holes in the feed wheel, said means 10 forming no part of the present invention.

Assuming that the parts are in the position shown, and that the shaft 30 is being driven in the direction indicated by the arrow Fig. 1, it will be seen, that through 15 the instrumentality of the crank arm 29 and link 28, the driver or plunger 38 and bar 21 will be moved downward and that the former will engage the head of the nail suspended from the pivoted supporter 69, and 20 start said nail downward, it being noticed that at this instant the core 74 is advanced and magnetized because of the completion of the circuit through the engagement of the conducting material and contact pin 34, 25 it being also noticed that the feed wheel is stationary because of the inaction of rock bar 18. Shortly after the driver or plunger has moved downward sufficiently to project the point of the nail through the alined hole 30 of the leather disk underlying the driver or plunger, the core becomes demagnetized through the rotary movement of the member 32 of the circuit making-and-breaking device and at about the same instant the cam 35 portion 24 of the slot of the downwardly moving bar 21, engages pin 20 and rocks the lower end of the rock bar outward, this movement incidentally returning the rock bar 11 from the position shown in Fig. 2 40 to its initial position to permit the pawl 14 to be forced by spring 15 into engagement with the next tooth of the feed wheel. In the withdrawal of the core it is incapable— due to the presence of residual magnetism— 45 of disarranging the nail because the lower end of the latter is held by stop 72, and its upper end is against the base of the bifurcation of the supporter, which supporter as will be readily understood is pushed aside under the pressure of the driver or 50 plunger on the nail head until the latter eventually slides off the upper side of the supporter, the opposite end of the supporter swinging afterward between the rock bar 18 and bar 21. The movement of the driver or 55 plunger continues until the head of the nail nearly comes in contact with the top of the disk or leather head, the feed wheel remaining stationary during the engagement of 60 pin 20 with the portion 22 of the slot of bar 21. Just before the downward movement of the driver or plunger is completed pin 41 carried by link 40, attains the lower end 65 of slot 42 and rocks the T-shaped rock lever 43 and hence through link 45 rock arm 46

and link 48, slides bar 49 upward. In this movement the rearwardly and upwardly projecting portion of slot 55 through engagement with pin 59, slides bolt 61 rearward until it forms a temporary partition 70 for the chute and it remains in such projected position until the lower end of the vertical portion of the slot 55 comes into engagement with said pin.

In the first half of the upward movement of the slide bar 49, the rock lever 56 remains stationary because of the engagement of its pin 58 with the vertical portion of slot 54. In the last half of such upward movement the downwardly and rearwardly inclined portion of said slot 54 engages said pin 58 and rocks the lever 56 and effects the withdrawal of bolt 60 from the chute and thus permits the nails to gravitate downward in the chute until the foremost is arrested by the projected bolt 61.

As the second half of the revolution of the crank shaft occurs, the driver or plunger and bar 21 are reelevated. During the re-elevation of bar 21, the cam portion 24 of 90 its slot rocks the rock bar 18 back to its original position and thus redisposes core 74 in the position shown in Fig. 1, and at the same time operates rock lever 11 and causes the same through the instrumentality 95 of pawl 14 to rotate the feed wheel one step in the direction indicated by the arrow, Fig. 2, this movement moving the nail equipped with the leather head from the contracted end 6^b of the slot 6^a in top 2, to a position 100 over the body portion of said slot in order that such nail may drop through said slot into a suitable receptacle, not shown, the leather disk occupying the next opening 10, being at the same time disposed vertically 105 below the driver or plunger and over the contracted end of the slot, ready to receive the next nail.

In the latter part of the second half of the revolution of crank shaft 30, the pin 41 at- 110 tains the upper end of slot 42 of the T-shaped lever and rocks the same and through the instrumentality of link 45, rock arm 46 and link 48, moves the slide bar 49 downward and the slide bolts 60 and 61 are re- 115 versely operated, that is bolt 60 is reprojected into the chute between the two foremost nails and then bolt 61 is withdrawn from the path of the foremost nail to permit the latter to slide downward and off the inclined 120 end of the chute and onto the nail supporter. Just before this occurs the advanced core 74 is reenergized by the reengagement of conductor 33 and contact pin 34, and as a result said core attracts and pulls the nail 125 squarely against its advanced end and between the nonmagnetic plates and incidentally against the base of the bifurcation of the nail supporter and the alined or free end of stop 72, so that such nail shall be held 130

in a vertical position and in perfect alignment with the driver or plunger and the perforation of the underlying disk.

A complete cycle of the operations has been described, all future operations being repetitions as will be readily understood. The machine operates with great rapidity and should any of the headed nails through the adhesion of the leather heads to the walls of the holes in the feed wheel fail to drop through slot 6^a into the receptacle below, they will be dislodged by a spring knocker 82 secured at one end to the standard 7, the free end of the knocker resting frictionally on the feed wheel and swinging successively down into the openings 10 thereof and dislodging as above stated, any nail, which fails to drop into the receptacle as explained.

From the above description it will be apparent that we have produced a nail leather-heading machine embodying the features of advantage enumerated as desirable which obviously is susceptible of modification in minor particulars without departing from the spirit and scope of the appended claims.

Having thus described the invention what we claim as new and desire to secure by Letters Patent, is:—

1. A nail feeding machine, comprising a movable nail supporter, a magnet to hold the nail in a vertical position, means for moving the nail endwise and the nail supporter out of the way of the nail, means to demagnetize the magnet, and means for withdrawing the magnet from operative position with relation to the nail during the movement of the latter.

2. A nail feeding machine, comprising a pivoted supporter for a nail, a movable magnet to hold the nail in vertical position,

means to impart endwise movement to the nail and cause the same to force the said supporter out of its path, means for demagnetizing the magnet, means for withdrawing the magnet from operative relation to the nail shortly after the movement of the same begins, and means for returning the nail-moving means to its original position.

3. A nail feeding machine, comprising a pivoted supporter for a nail, a movable magnet to hold the nail in vertical position, means to impart endwise movement to the nail and cause the same to force the said supporter out of its path, means for demagnetizing the magnet, means for withdrawing the magnet from operative relation to the nail shortly after the movement of the same begins, means for returning the nail-moving means to its original position, and means to return the magnet to its original position.

4. A nail feeding machine, comprising a movable nail supporter, a magnet to hold the nail in a vertical position, means for moving the nail endwise and the nail supporter out of the way of the nail, means to demagnetize the magnet, a movable stop engaging the nail at the opposite side thereof from the magnet and nearer its point than said magnet, and means for withdrawing the magnet from operative relation to the nail during the said movement of the same.

In testimony whereof we affix our signatures, in the presence of two witnesses.
